UNITED STATES PATENT OFFICE.

ENOCH ARTHUR PEARSON, OF CHICAGO, ILLINOIS.

OIL-BURNING MECHANISM.

Application filed December 15, 1924. Serial No. 755,835.

To all whom it may concern:

Be it known that I, ENOCH ARTHUR PEARSON, a citizen of the United States, and a resident of the city of Chicago, in the county of Cook and State of Illinois, have invented certain new and useful Improvements in an Oil-Burning Mechanism; and I hereby declare that the following is a full, clear, and exact description of the same, reference being had to the accompanying drawings, and to the numerals of reference marked thereon, which form a part of this specification.

This invention relates to oil burning mechanisms and has for its object the provision of an efficient oil burning device and one which may be readily removed from the furnace for inspection, cleaning, renewal or repair.

With the above and other objects in view, as will be apparent, this invention consists in the construction, combination and arrangement of parts, all as hereinafter more fully described, claimed and illustrated in the accompanying drawings.

On the drawings:

Figure 1 is a vertical elevation in section, showing a device embodying this invention.

Figure 2 is a plan view of the same.

Figure 3 is a section along the line 3—3 of Figure 2.

Figure 4 is a section along the line 4—4 of Figure 2.

Figure 5 is a detail view of the mechanism for automatically cutting off the oil supply.

As shown on the drawings:

Numeral 1 represents a fire box of a furnace having a door 2 communicating therewith from without said furnace. Numeral 3 represents an air chamber in said furnace in which air is adapted to be compressed for combustion with the oil in said furnace. A casting 4 is supported between the furnace proper and said chamber 3. The casting 4 is supported on grate bars 5 resting on bearer bars 6 which are suitably supported in the boiler. Suitable closing means 7 surrounds the casting 4 on the grate bars for restricting the communication between the furnace 1 and the air chamber 3 through apertures 8, 9 and 10 in the casting 4. Removably secured on the casting 4 and communicating with the apertures 8 and 10 therein is a manifold 11 having a downwardly disposed aperture 12 therein through which air communicated to said manifold through said apertures 8 and 10 is

adapted to be distributed to a burner 13 supported on the casting 4 beneath said manifold 11. Secured to the upper side of the manifold 11 is a ring bolt 11^a adapted to receive the end of a rod or the like for facilitating the removal of said manifold. The burner 13 is of substantially conical shape and has centrally positioned therein a pipe 14 which communicates through a valve 15 to a supply line 16 for supplying oil to the burner. The burner 13 presents substantially a spherical surface immediately surrounding the opening of the pipe 14 therein. Below the spherical surface of the burner are a series of concentric stepped grooves 17. The spherical surface of the burner is adapted to more evenly distribute the oil rapidly over the surface of the burner. The grooves 17 are adapted to retard the oil flowing down side of the burner, insuring complete combustion thereof. Lugs 18 on the burner are adapted for engagement beneath the heads of the studs 19 secured in the casting 4. The aperture 9 in the casting 4 is adapted for communication between the chamber 3 and the bottom of the burner, the burner being shaped at its lower edge for permitting the air to flow therebeneath from the lower side of the burner to the upper side thereof. An overflow pipe 20 is secured to the casting 4 and communicates therewith for carrying away any unconsumed oil from the burner. The end 21 of the pipe 20 (Figure 5) is positioned over a bucket 22 secured to a suitable valve 23 in the supply line 16 for shutting off the oil communicated therefrom to the valve 15 when the oil in the bucket 22 reaches a predetermined amount. A valve 24 in the line is adapted to be opened to admit fuel to the valves 23 and 15.

The operation:

Air in the chamber 3 is adapted to enter a manifold 11 through the apertures 8 and 10 and be distributed over the aperture 24' over the upper surface of the burner. Likewise air passes through the aperture 9 to the under side of the burner under the lower edges thereof to the oil in the burner; said air unites with the oil insuring the complete combustion thereof. It is also to be noted that the air in both cases is preheated before uniting with the oil. The oil which is pumped to the center of the burner descends by gravity over the spherical surface to the steps 17. In case of too great a sup-

ply of oil or if the burner for any reason should go out, the unconsumed oil will flow out through the oil return pipe 20 to the drip bucket 22 which operates the valve 23 for automatically shutting off the oil and preventing danger of explosion when the furnace is again started up.

- Another important feature is the ready removal of the burner. This can be effected 10 by removing the valve 15 by means of unscrewing the union secured thereto, slightly rotating the burner to release the lugs 18 from underneath the heads of the studs 19, elevating the manifold 11 out of the way 15 and then pulling the burner portion out through the furnace door 2, pulling the oil inlet pipe 14, outwardly thereafter and therewith through the aperture 9. It will be seen that the structure arrangement of 20 parts of the mechanism embodying this invention provides a very economical and efficient burner, one which is readily removable for inspection, cleaning, renewal or repair and which is automatically guarded 25 against overflow and danger of explosion.

I am aware that many changes may be made, and numerous details of construction may be varied through a wide range without departing from the principles of this 30 invention, and I therefore do not purpose limiting the patent granted hereon, otherwise than necessitated by the prior art.

I claim as my invention:

1. An oil burner comprising a circular member having a convex cross-section, an integral hemispherical portion in the center of said member, means in said portion for ejecting oil over the surface thereof, and integral concentric stepped grooves on said

member joining the lower edge of said 40 hemispherical portion.

2. The combination with a furnace having an air chamber therein, of a burner situated over said chamber, of an air passage communicating with said chamber and said 45 burner and a pipe connected to said burner for ejecting oil over the surface thereof, a readily accessible connection communicating to said pipe, means on said burner for readily releasing the same from engaged 50 position over said chamber for permitting the removal of said burner, the pipe connected thereto being adapted to be drawn outwardly thereafter and therewith through said air passages when said readily accessible connection has been removed, said connection being accessible from without said furnace.

3. The combination with a furnace having an air chamber therein, of a burner situated over said chamber, of an air passage communicating with said chamber and said burner and a pipe connected to said burner for ejecting oil over the surface thereof, a readily accessible connection in said pipe, means on said burner upon a slight rotational movement thereof to release the same from rigid engagement over said member, the pipe connected thereto being adapted to be drawn outwardly thereafter and therewith through said air passages when said readily accessible connection has been removed, said connection being accessible from without said furnace.

In testimony whereof I have hereunto subscribed my name.

ENOCH ARTHUR PEARSON.
